Primary Examiner — George D. Kirschbaum*Assistant Examiner* — Jasmine L. Coleman(74) Attorney, Agent, or Firm — Banner & Witcoff, Ltd.(57) CLAIM

The ornamental design for a mosaic tile as shown and described.

DESCRIPTION

FIG. 1 is a front view of a mosaic tile showing my new design; and,

FIG. 2 is a front isometric view thereof.

The broken lines depict portions of the mosaic tile which form no part of the claimed design.
